UNITED STATES PATENT OFFICE

ASA R. CHASE, OF MIAMI, OKLAHOMA

JIG

Application filed November 17, 1926. Serial No. 148,904.

This invention relates in general to an apparatus for separating ore or other mineral from rock or lighter material and more particularly to an ore jig of the type wherein a pulsating column of water is used in conjunction with a grate to effect classification of a bed of material.

The object of the invention is to provide a jig of this character which is constructed of tank or sheet steel and angle bars or structural steel so organized that the jig is made up of a plurality of similar detachable cells or units. By virtue of the detachable cell or unit construction the jig can readily be converted into a rougher, cleaner, chat, or sand jig. Moreover, the jig can be constructed to fall in either direction.

Another object resides in the provision of a jig wherein the pulsation set up in the column of water used to effect classification in the bed of materials operated upon encounters a minimum of resistance, the water having a free and easy action and movement which increases the capacity of the jig and also makes possible a more efficient operation while reducing the amount of power that need be expended.

A further object is to provide a jig which by virtue of the novel features herein mentioned may be of less height, thereby saving the additional elevation of the mill dirt that would otherwise be required.

Another object resides in the provision of a jig wherein an adjustable throat is provided to enable the jig to be converted for use with lighter or heavier ores as well as adapted for diverse jiggling functions.

Another object is to provide a jig having an adjustable overflow tail board at the lower end of each cell or unit of the jig whereby the depth of the bed in each cell may be varied.

A still further object resides in the provision of a jig having a plurality of chat draw offs in each cell, one chat draw off being lo-

cated at each end of each cell, thereby making it possible to reverse the jig and also providing for the drawing off of the excess bed from the upstream chat draw off should this be desired.

Other objects and advantages reside in certain novel features of the construction, arrangement and combination of parts which will be hereinafter more fully described and particularly pointed out in the appended claim, reference being had to the accompanying drawings forming a part of this specification.

Figure 1 is a view in side elevation showing a jig constructed in accordance with the present invention,

Figure 2 is a view in horizontal section on the line 2—2 of Figure 1,

Figure 3 is an enlarged fragmentary view partly in side elevation and partly in longitudinal vertical section,

Figure 4 is a view in transverse vertical section, parts being shown in elevation for the sake of illustration, and

Figure 5 is a detail view showing how the tail boards are adjustably supported.

Referring to the drawings it will be seen that the jig constituting the present invention is made up of a number of similar cells or units, designated generally at 1. Each cell 75 or unit 1 includes side walls 2 and 3 and a semi-circular bottom wall 4 extending between and merging into the side walls 2 and 3. The jig structure is completed by transverse partitions 5 and longitudinal partitions 6, the partitions 5 at the ends of the jig constituting the end walls thereof. The side walls, bottom walls and partitions are all constructed of tank or sheet steel. U-shaped angle bars 7 are provided and extend around the margins of the sides and bottom of each unit, the U-shaped angle bars 7 having flanges 7^a which snugly fit against and are riveted to the sides and bottom and also having other flanges 7^b which snugly abut and are riveted 90

to the partitions 5. The partitions 6 are connected to the partitions 5 and are braced and reinforced by means of angle bars 8 having flanges 8^a abutting and riveted to the partition 6 and flanges 8^b abutting and riveted to the partitions 5. The jig is supported on beams 9 of channel iron in any suitable manner and preferably by means of legs 10 of angle iron riveted to the channel and to the partitions 5. The partitions 5 are of rectangular form and project beyond the bottom of the jig, these partitions being notched to receive the channel beams 9. Angle braces 11 may be provided between certain of the partitions 5 and a channel beam 9. Of course, the braces 11 as well as the legs 12 are riveted to the partitions which they connect. It is to be understood that suitable packing may be provided between the partitions and the flanges of the angle bars which they engage and also between the side and bottom walls and the flanges of the angle bars which they engage.

Each unit or cell of the jig as thus constructed has a plunger compartment 15 in which a plunger 16 is operatively fitted, the plunger being carried on the plunger stem 17 having an eccentric strap 18 at its upper end co-operable with an eccentric 19 provided on a line shaft 20. The line shaft is suitably supported in bearings provided therefor on transverse bars 21 extending between and connected to the ends of the angle bars 7 and 8. Each cell also includes a compartment 25 having a grate 26 which supports the bed of material to be classified. The compartment 25 communicates with the compartment 15 through a throat or open space 26' defined between the bottom 4 of the compartment and the lower edge of the partition 6, the partition 6 terminating above the bottom 4. For the purpose of varying the area of this throat an adjustable throat plate 27 is provided and is fastened in any one of a number of adjustments by means of rivets or bolts or other fastening means 28. If bolts and nuts are employed the partition 6 and adjustable throat plate 27 are provided with a plurality of selectively registerable bolt holes to afford the necessary adjustment. By varying the area of the throat the jig may be adapted for use with light or heavy ores as well as adapted for various diverse jigging functions. The grate 26 is made up of a plurality of spaced grate bars 29 mounted on a grate rest made up of angle bars 30 and 31 which are riveted or otherwise suitably fastened in place on the tank.

The partitions 5 at the lower end of each cell carry adjustable tail boards 35, each tail board 35 being located at the low end of the grate of the adjacent cell and having vertical slots 36 with which bolts and nuts 37 contact to hold the tail board in vertical adjustment. The bolts and nuts 37 also extend

through bolt holes provided in the partitions 5. By varying the height of the tail boards 35 the depth of the bed of material being classified, which bed is built up on the grate 26, is varied.

The side wall 3 of each cell or unit has two openings formed therein, designated at 41 and 42, the openings constituting chat draw offs. Usually only one opening is used for drawing off the chats and, of course, the other openings at such time is closed by a suitable closure plate which may be releasably secured to the wall 3 by any suitable means. Provision of the two chat draw off openings makes it possible to construct the jig so that it falls either to the right or to the left. The upstream chat opening may also be used to draw off the excess bed. In the bottom of each cell or unit a discharge pipe 45 is provided and has a manually controlled valve 46 incorporated therein. The pipe 45 discharges into a chute or other suitable conveyor 47 for carrying away the cleaned ore.

Each cell or unit of the jig which applicant provides operates broadly in accordance with the usual practice in that the plunger in each cell or unit sets up pulsations in the column of water in the compartment 25 and the pulsations serve to effect classification of material which builds up in a bed on the grate 26. The advantages of applicant's invention resides in the rounded bottom which permits the water to partake of the free and easy action and to be pulsated with the expenditure of less power than has been required heretofore.

Another feature resides in the provision of the adjustable throat. The adjustable tail board provides a convenient means for varying the height of the bed in each cell. The provision of a plurality of chat draw offs makes the jig reversible that is it may be constructed to fall in either direction. Along with these advantages is the advantage of the all steel construction which is of less weight, less bulk, fire proof as well as more durable and efficient. All of the elements of the jig preferably are constructed of steel except the plunger and except the walk board that is usually provided along one side of the jig.

It is obvious, however, that other suitable known materials, such as wood or concrete, may be used in the construction of a jig embodying the invention and that many modifications and adaptations of the form of the device which is illustrated in the drawings may be made without departing from the spirit and scope of the invention. I therefore consider as my own all such modifications and adaptations thereof as fairly fall within the scope of the appended claim.

I claim:

A casing including a plurality of longitudinally aligned U-shaped sheet metal members arranged in edge to edge relation, a plurality

of parallel partitions extending transversely in the sheet metal members with their outer edges passing between the opposed edges of two adjacent sheet metal members and projecting laterally therefrom, and U-shaped angle irons embracing the sheet metal members at opposite sides of the laterally projecting edges of the partitions and secured to the latter and adjacent edges of sheet metal members.
